UNITED STATES PATENT OFFICE.

ISAAC NEWTON FORBES, OF LAWRENCE COUNTY, DAKOTA TERRITORY.

ROTARY ENGINE.

SPECIFICATION forming part of Letters Patent No. 274,478, dated March 27, 1883.

Application filed July 26, 1882. (No model.)

To all whom it may concern:

Be it known that I, ISAAC NEWTON FORBES, of Lawrence county, Territory of Dakota, temporarily residing at Washington, in the District of Columbia, have invented a new and useful Improved Trochilic or Rotary Engine, of which the following is a specification.

The subject of my invention is a trochilic or rotary engine with two piston-wheels, with two teeth to each wheel attached to one shaft, and two abutment-rollers to each piston-wheel, which may be of one-half the circumference of the piston-wheel, and are geared so as to rotate in unison therewith, and are formed with cavities to pass the piston-teeth and with counterbalance-chambers at the opposite sides; also, with a pair of automatic fourfold cut-off valves at diametrically-opposite points in the cylinder-casing for each respective piston-wheel adjacent to the abutment-rollers, serving to cut off the steam at any desired proportion of the revolution consistent with the design or make of the engine, causing it to work steam or other motor power expansively. The relative positions of the piston-teeth on their respective piston-wheels stand quartering, or at an angle of ninety degrees to each other. The piston-teeth are formed with tongues or shanks fitting in longitudinal grooves in these wheels and secured by bolts. They are also provided with packing-pieces pressed outward automatically by springs or steam, or both, in contact with the inner surfaces of the cylinders. The working-surfaces of the cylinders and of the piston-wheels are for the most part made up of removable segments composed of Babbitt or other suitable metal cast into suitable seats, or of other hard metal slipped in, as hereinafter described. The steam is taken in in a direction radial to the cylinders around which it is conducted, so as to enter at two diametrically-opposite points, in order to balance the pressure, while the exhaust-passages are arranged on the outside of the live-steam channels in the respective cylinder-cases, in order to prevent the live steam from loss of heat by radiation, and at the same time make firmer and more rigid steam cylinders or casings therefor.

In order that the combination may be fully understood, I will proceed to describe it with

reference to the accompanying drawings, in which—

Figure 1 is a transverse section through the casing and cylinder, illustrating the shaft, piston-wheel, abutment-rollers, and valves. Fig. 2 is a horizontal plan view of the engine, partly in section. Fig. 3 is a vertical longitudinal section of the engine, the base being broken. Figs. 4 and 5 are outside views of outside heads, showing tappets and cut-off valve-gear. Fig. 6 is the central head, partly in section, with induction-steam fitting partly broken off, the section-line of the center bearing being on line with the surface of the head and the remainder of the section being central. Figs. 6^a and 6^b are sectional views of a central head on the line 6^a, Fig. 6. Fig. 7 is a longitudinal central sectional view of the main-shaft bearing in one of the outside heads partly broken. Fig. 8 is a top view with cap 263^a full, partly removed, showing pinion and gear full, with shaft-bearings and ring in section on the line 8 8, Fig. 7, this cap 263^a being shown in section in Fig. 7. Cap 263^a forms the inner bearing of the pinion-shaft 266^a and a protection for the tooth-gear upon the adjustable ring 263, from interruption of the capillary material used in the oil-chamber of the head. Figs. 9 and 10 are bearing-pieces, shown in full and section. Fig. 11 is a transverse section of the bearing-segments detached on the line 8 8, Fig. 7. Fig. 12 shows a sectional view of pinion 265 and shaft 266 complete, shown in Fig. 7. Fig. 13 is a detailed longitudinal sectional view, illustrating the mode of connecting the valve-levers to the valve-stem. Figs. 14 and 15 are transverse sections, illustrating different modes of setting out the packing strips of the piston-teeth, either by steam or spring adjustment, or both if required. When steam is used the side surface of the packing strips and surface in the tooth, where convenient, are water-creased. Fig. 16 is an end view of one of the teeth detached, showing the end packing-piece removed. Fig. 17 is a longitudinal section of an end of the tooth, showing the end packing in elevation and end of packing-strip in section. Fig. 18 is a face view of one of the teeth. Fig. 19 is a side view of the same. Fig. 19^a is a side view of the packing-strip detached. Fig. 20 is a cross-section through the casing,

cylinder, &c., illustrating a modification of Fig. 1, showing a twofold valve and parts to suit, instead of fourfold, as in the other case. Figs. 20^a, 20^b, 20^c, 20^d, and 20^e are detailed views in section and full of a modified two-fold double-faced valve. Fig. 21 is a detached sectional view of the outside head, with bearing-case and bearing, illustrated in Fig. 21^a, removed. Fig. 21^a is a longitudinal section of the bearing-case and bearing complete removed from the head. Fig. 21^b is a sectional view of four bearing-pieces in position on the line 21^b, Fig. 21^a. Fig. 21^c is a top view of the adjustable bearing-case 21^a.

15 To the main shaft 131 are secured two piston wheels, 132 and 132^a, connected by gearings 133 and 134 with abutment-rollers 135, so that the said rollers will rotate in unison with the piston-wheels 132 and 132^a without any slip between their peripheries. Straight gearing 133 and 134 is provided at one end and helical gear 168 and 169 at the other end of the engine. (Shown in Fig. 2.) Each piston-wheel carries two piston-teeth, 136, at diametrically-opposite points, the said teeth being formed with tongues or shanks 137, portions of which are dovetailed in grooves or recesses in the wheels, and secured by bolts 138. Said teeth are also provided with shoulders, 25 serving to hold the surface-pieces 141, hereinafter mentioned. In the faces of the teeth are packing-pieces 139, pressed outward by springs or steam, or both, and where steam is used the sides of the packing-strips and inner surfaces of the teeth should be water-creased or grooved, where convenient, to prevent leakage, the said pieces being pressed in contact with the inner surfaces of the cylinders 140.

The working-surfaces of the piston-wheels 40 132 and of the cylinders 140 are made with removable segments 141 and 142. The piston-wheels and segments fitting them are fitted in T-shaped grooves and tongues, as herein illustrated, or in any suitable manner, so as to permit 45 the said surfaces to be readily and economically removed and renewed, if desired. These removable surface-pieces may be made of Babbitt or other metal poured around in a templet of the exact shape, or the surface-pieces made to fit the T-shaped grooves and 50 tongues of the wheel of steel and tempered and pressed in their respective positions; or they may be made of hard brass or other suitable material. The surface of the wheel is preferably of very hard metal, the periphery of which must be made perfectly true. The removable surface-pieces in the cylinders may also be made of Babbitt or other suitable metal poured in, or may be composed of a cylinder or band 55 pressed in position to fit and to be replaced when worn. The removable surface-pieces attached to the faces of the cylinder-heads are illustrated at 142^a in Fig. 3.

The abutment-rollers 135 are formed with 60 cavities 143 to permit the passage of the piston-teeth 136 in their revolutions. The abutment-rollers being one-half of the circumfer-

ence of the piston-wheel and the latter carrying two teeth, it will be evident that the single cavity 143 in each abutment-roller will be 70 presented to receive each of the two teeth of the piston-wheel in succession, while the piston-wheel and the abutment-rollers are, as stated, geared so as to rotate in unison without any slip between their peripheries, the 75 abutment-rollers necessarily performing two revolutions for every revolution of the piston-wheel. Similar removable segments or surface-pieces are provided in the abutment-roller casings, as shown at 144, Fig. 1, which surface-pieces may be composed of Babbitt or other metal poured in around a templet, which should be held in an exact central position and of the exact size required; but it may be dressed out and fitted in, corresponding with 80 the shape of the recess; or they should be made the best shape to receive the surface-pieces. The casing in which the abutment-rollers work should be water-creased, similar to the surfaces of the abutment-rollers; also, 85 the main cylinder in which the piston-wheel works should have water-creases similar to those in the piston-wheel to prevent the passage of steam between the surface of the teeth and that of the cylinder, thus insuring safer 90 joints, the surfaces of the packing-pieces in the teeth being likewise water-creased.

145 represents holes or chambers in the abutment-rollers for counterbalancing the recesses for the piston-teeth to pass and to lighten 100 the abutment-rollers.

The live steam is introduced into the top of the center head, 148, through inlet 146, and thence conveyed to points 149, about midway between the end heads, 147, and center head, 105 148, and from thence into the respective parts of the cylinders. The live steam is conducted partly around the cylinder, where it is delivered through the valve-seats and the recesses in the valves into the cylinder at diametrically-opposite points, in close proximity to the abutment-rollers 135, by means of four-fold oscillating cut-off valves 150, so that the steam may be worked expansively during the latter part (more or less) of the movement of 110 the teeth between the abutment-rollers. These valves have holes crossing each other, leading to opposite quarters, between the adjustable valve-pieces, which convey live steam to the opposite quarters thereof, thus holding the 115 valve in equilibrium, pressing the valves to their seats by the pressure of steam beneath the flanges thereof. They are pressed out by means of springs, also, and, if desired, steam may be employed in connection therewith beneath the shanks in the valve-frame, and water-cuts placed in the valve, as more fully described in another application of even date herewith, marked "C."

The exhaust-ports are shown at 152, and are 120 constantly open, the escape of live steam to said exhaust-ports being prevented by the closing of the cut-off valves 150 and their remaining closed until the piston-teeth 136 have

passed the abutment-rollers 135 and cover the inlets 151, respectively, when the valves are being reopened and steam admitted behind the teeth, between them and the abutment-rollers, thus continuing the force alternately upon the respective piston-wheels.

The exhaust-steam passage 153 extends around the circumference of the cylinder-casing 140^a, on the outside of the live-steam passage 149, after entering the casing proper, so as to protect the latter from cooling and consequent loss of pressure of steam. A casing filled with a non-conductor of heat may also inclose the casing wholly or partially, as may be desired.

The automatic gear for operating the cut-off valves is shown in Figs. 4 and 5, that in Fig. 4 consisting of valve-levers 154, secured by pins, &c., to the end of the valve-stems, and each constructed with two arms, 155 and 156, formed with curved fingers 157, adapted to receive the impact of tappets 158 and 159, which are connected respectively with the under side of the main gear-wheel on the main shaft and the under side of the pinion gear-wheels on the abutment-roller shaft in such manner that the contact of the main gear-wheel tappet 158 with the arm 155 will close the cut-off valve when the tooth has performed the desired part of its movement between the abutment-rollers, and when the teeth cover the inlet ports 151 the abutment-roller tappets, having come in contact with the arms 156, reopen the valves 150. Dotted lines for the respective teeth indicate their position when steam is first let in. The second dotted lines indicate the position when the valve is sufficiently open to let the steam in between the teeth and the abutment-rollers.

In Fig. 4 full lines indicate the position of the valve-gear when the valves are open for full head of steam, while dotted-lines of the valve-levers indicate their position when the valves are closed for using steam expansively. *aa* and dotted lines indicate the position of the piston-teeth in the cylinder at the time the full head of steam is let on, and shows their relative position to the valve-gear.

The reverse method of cutting off and letting on steam of that shown in Fig. 4 is shown in Fig. 5. In Fig. 4 the cut-off tappets were secured to the main gear-wheel and the let-on tappet to the respective abutment-roller wheels, which, when cut off, close the ports filled with live steam from the valve-seat and leave the port from the piston-wheel open in the valve, while in Fig. 5 the let-on tappet is on the main gear-wheel and the cut-off tappets are on the respective abutment-roller gear-wheels, which is readily seen from the dotted lines of the relative position of the valve and steam ports through into the cylinder. This leaves the main live-steam port open into the valve-seat continually and cuts off the live steam from the piston-wheel into the valve-seat, thus leaving the pressure of live steam, which has a greater head for a continual pressure out upon the flanges of the adjustable valve-pieces to assist the springs, or the steam, if used, within

to hold the adjustable valve-pieces upon their faces, especially the one covering the inner port, which has the counter-pressure upon its face 70 to open it, which is continually diminishing, whereas in Fig. 4 the steady live pressure from the boiler while the valve is closed, covering the inlet-port into the valve, has the tendency to open the valve, while the pressure from 75 within the cylinder against the flanges of the valve-pieces, &c., is variable. The difference is here shown, so that choice may be taken. I consider that shown in Fig. 5 as preferable, 80 though both are good.

In Figs. 4 and 5 there are two classes of valve-levers, though their shapes for contact with the tappets are the same. 154 receives the engine-bolts in the curved slots 154^a in the end, limiting the motion of the latter to the 85 proper distance for letting on and cutting off steam. These bolts have removable sleeves, to protect them from injury by the action of the valve-lever. The valve-lever 154^a has but one bolt, extending from the head up between the 90 arms, to perform the same function of limiting the play of the valve in cutting off and letting on steam. This bolt has also a protecting-sleeve, to be removed at will, and the stop, permitting the play of the lever on the bolt, 95 equals the play of the valve. The latter lever is, perhaps, the most simple, though either may be used.

It will here be noticed that the valve-tappets, respectively in Figs. 4 and 5, have much more of their continued circumferential surface than those used in cut-off reversing-engines described in other applications of even date herewith. The object of this is to hold the end of the valve-levers in their respective 100 positions—either open or closed, as the case 105 may be—until their opposite tappets are ready to take the opposite arm. When the tappet leaves the arm the others take the opposite end to reverse the valve. Full lines indicate 110 the position for cutting off and letting on, while dotted lines indicate the relative position of the piston-teeth and recesses in the abutment-rollers.

In Fig. 5 the cut-off tappets upon the abutment-roller gearing have provisions made for setting forward or back, one having a slot, the other having holes in it. Either one of these devices may be adapted for the purpose of increasing or decreasing, as the case may be, the relative proportion of the revolution before cutting off for using steam expansively, which tappets are secured firmly to the gear-wheels, respectively. A double engine of this character, while working steam or other motor-fluid expansively and in the most economical manner, is rendered smooth and uniform in its action by the induction and eduction of steam upon the respective piston-teeth and in harmony with the momentum of the pulley, and by the complete opening of one pair of valves before the others, as above shown, the piston-teeth being arranged in alternate positions for this purpose, as before explained.

The construction of the casing and the arrangement of the steam passages and ports through the same are very simple. The outer and inner casing are united with partitions or bridges and ties, as may be desired, which will form rigid cylinders and casings for the working parts of the engine. The inlet and exit channels for the induction and exhaust steam are indicated by arrows in the respective figures, 1 and 20, the latter being a modification of the former, and forming an extremely simple casing and cylinder with their adjuncts. The respective walls of the induction and exhaust ports are united firmly by bridges, connecting the same together at short distances apart, leaving sufficient area for receive and exhaust ports.

The gearing which connects the piston-wheels with the abutment-rollers, so as to compel them to rotate in unison, is represented in plan view, at 133 and 134, in Fig. 2 in the form of simple cog-wheels and pinions at one end and helical gear 168 169 at the other, and thus guarding against the possibility of lost motion by end adjustment of the helical gear or gearing to suit; or the helical gear may be used at both ends of the abutment-rollers and the main shaft, as shown in Fig. 3; or the gears may be cut in two transversely and adjusted to prevent lost motion of rotary engines, which will be the subject of other applications soon.

A horizontal longitudinal central section of the center head is illustrated on the line 6^a of Fig. 6, with the convex movable part of the head which supports one end of the main bearing-case and bearing removed, which latter is illustrated in detail in Fig. 6^b. This part is made separate, and screws into the main part 40 of the center head and forms a part thereof. It also screws upon the end bearing-case, and forms a support thereto, thus completing the head, which, when secured to its position, answers the same purpose as when cast solid in one piece. The object of casting this piece separate is for the purpose of inserting the center bearing, without which it would be impossible to do so, as herein shown.

The adjustable bearings 31 and removable pieces 32 are removed from their positions in the center head, permitting the center journals of the abutment-rollers to slip in their respective bearings when the adjustable bearings 31 and removable pieces 32 are replaced in their position. The pieces may be provided with tongues, with corresponding grooves in their seats in the slots or recesses in the head, in which they fit for the purpose of securing them laterally to the head in their positions; or they may each be provided with grooves and separate tongues slipped in for the purpose of performing the same office. These removable pieces are secured to the head by bolts 33 in their positions, and held firmly there-to, the bolts being secured from turning by lock-washers.

The automatic followers 34 have collars 42,

which receive the pressure of the springs 36, and auxiliary springs 42^a are placed at the end for holding the adjustable bearing-piece, abutment-roller, and journal in their respective positions, as shown in Figs. 6 and 6^a.

The catch 43^a holds the cap-nut 37 from turning, and is held in position by a ring. The spring-catch 43^a is thrown out of connection 75 with the cap-nut by the application of a wrench or key which turns the said cap-nut. This head is fully explained in other applications of even date herewith.

In the several heads of the engine are located all the bearings proper. The main-shaft bearing in the center head, as illustrated, has four adjustable bearing-pieces, 251, placed at opposite quarters, with two projections on the back of each bearing-piece, which pass through 85 mortises in the bearing-case, and have eccentric backs, over which a ring, 252, is fitted that encircles them, with recesses therein containing eccentric segments corresponding with the eccentric backs of the bearing-segments. 90 This ring has a worm tooth-gear upon part of its periphery, with an endless screw fitting therein on a shaft, 255, extending to the outside of the head, (shown and described fully in other applications of even date herewith,) which, 95 when turned by key or wrench, adjusts the bearing centrally with the cylinder upon its shaft, thus securing a continual central position of the piston-wheels to their cylinders, which, as before remarked, is indispensable to 100 the success of the engine.

I do not confine myself to two eccentric backs and two mortises in the bearing-case for each adjustable piece; nor do I confine myself to four bearing-pieces for the main-shaft bearing 105 of the center head; nor to one ring, worm-gearing, shaft, &c., for holding and adjusting the bearing-pieces, as the size and length of the bearings have much to do with the construction, the number of bearing-pieces, and number and size of the mortises through the casting, and the projections passing through the same and their locations.

The main-shaft bearings in the outer heads are composed of adjustable bearing-pieces 261, 115 fitted in their respective casings 264. (See Figs. 7, 8, 9, 10, 11, 21^a, and 21^b.) The bearing-case is cast separate from the outer head (see Fig. 21^a) for the purpose of inserting the bearing, which, when screwed in the head and secured from turning by bolt 147^a or otherwise, forms a part of the head, as though cast in one piece. This casing is first bored out the proper shape and the ends dressed to receive the ends of the adjustable bearing, as shown 120 in Fig. 21^c, with the ends of the bearing-segments dressed to fit, which form partial radial guides to the adjustable pieces, they then being placed in position and a shaft or templet of the proper size placed in the bearing. After the pieces are all in position Babbitt or other suitable metal is poured in the casing, which fills up all the vacant places, screws or pins being first inserted in the casing between the

bearing-pieces to hold the Babbitt. Holes may be bored in the casing, if required, or either one used to secure the Babbitt in position; or other metallic pieces, dressed to suit, may take the place of the Babbitt, and secured by screws to the casing, forming complete guides to the bearing-pieces. The casing is provided with mortises through it for the purpose of allowing the inclined backs 262 and 262^a of the bearing-segment to pass through, which fit the inclines of an encircling ring, (see Figs. 7 and 8,) which ring incloses the bearing-case and bearing, with corresponding inclines upon its inner surface, corresponding with the inclined backs of the bearing-segments. It also has upon its inner surface a screw-thread, filling a corresponding screw upon the outer surface of the bearing-case 264. These screw-threads enable the ring 263 to move longitudinally when turned thereon by means of a toothed gear upon the outside of the ring 263. (See Figs. 3, 7, and 8.) These teeth fit the pinion 265, secured to the bolt or shaft 266^a, with its appendages, (see Figs. 7, 8, and 12,) which, when the wrench is applied through the outer cover in the main gear-wheel, imparts the necessary rotary motion to the encircling ring 263, and thus screws it upon the bearing-casing in order to move the encircling ring longitudinally, and so press the inclined backs of the bearing-segments in upon the shaft, and thus secure a central adjustment of the bearing upon the main shaft. By this means a continued central position of the piston-wheels to their cylinders is maintained, which is indispensable for the success of the trochilic or rotary engine. This position is secured to each of the main-shaft bearings.

In the end heads, as in the center-head main-shaft bearings, I do not confine myself to the number of bearing-segments employed in each bearing, or the number of inclined backs thereon, or the number of mortises in the casing for the backs to pass through, or the number of pinions employed to turn the encircling ring, or the number of rings employed to fill that office of adjusting the bearing-segments centrally, the size, shapes, and number of bearing-segments, construction of casing, and shape of ring being governed greatly by the size and length of bearings.

A horizontal central sectional view of the outer head, with bearing-casing and bearings complete removed, is illustrated in an enlarged view in Fig. 21. The bearing-case, with bearings therein, is separately illustrated in Fig. 21^a. Fig. 21^b illustrates the position of the bearings removed from the case in a sectional view on the line 21^b of Fig. 21^a. Fig. 21^c is an end view of the bearing-case 264.

The sectional views in Figs. 8 and 11 show methods of manufacturing the different bearing-segments, three of these segments being babbitted and one shown solid. Either the solid or babbitted bearing-pieces should be adopted, but not conjointly; but a harder bearing-piece may be used in the bottom to sustain the extra

wear produced by the weight of the piston-wheel, &c., thus assisting the maintenance of the central position. The inclined projections in two of the bearings are smaller, showing the different methods of construction only.

In Fig. 11 the four bearing-pieces are illustrated in detail view, partly in section and partly in full in their relative position as they would be in the casing.

In Fig. 7 the adjusting-bolt 266 and pinion 265 are shown in gear, with the adjustable toothed ring 263, with all the appendage in the casing complete, and details of the pinion 265 and of the shaft, with all its appendages, and a broken piece of the bearing-casing are shown in Fig. 12. 266 is the bolt proper. 267 is the adjustable pin which fits in the bolt. 269 is the coil-spring in the bolt around the pin. 268 is the rivet which passes through the ratchet-ring 270 from side to side, and through a slot in the bolt and tightly through the adjustable pin 269, the ends being riveted sufficiently to hold all in position when the bolt is placed in position in the casing. The annular ratchet cap ring 271 is placed over the bolt in the recess of the casing, and bolted or riveted firmly thereto, the pinion being placed upon the inner end of the shaft or bolt and secured thereto by rivets or screws or otherwise, and in gear with the adjustable toothed ring.

It is evident that when the wrench is applied to the end of the bolt or shaft firmly with the inner portion pressing against the outer end of the adjustable pin 267 that it will play in the seat in the bolt and carry the ratchet-ring 270 in the recess in the casing made to suit, and thus throw the two ratchet-faces out of gear and allow the bolt to turn freely, which carries the pinion, and thus turns the adjustable toothed ring 263 upon the screw and adjusts the bearing, as heretofore stated, to take up the wear upon the main-shaft bearing, and when the wrench is withdrawn the ratchets at once are thrown in gear by the spring pressing outwardly upon the shoulder of the pin. The wrench has to pass through holes in the outer end covers and in the main gear-wheels to get to the adjustable bolt 266, for adjusting the bearings by the inclines upon their backs coming in contact with the inclines in the adjustable rings, thus securing a continuous central position of the piston-wheels to their cylinders. Two or more of these pinion-wheels and appendages complete, as described or otherwise, instead of one in contact with the toothed gear of the adjustable ring 263, placed at convenient parts of the casing, may be used, if necessary.

270 and 271 are ratchet-rings shown in full and in section separated and together, respectively.

The piston-wheel teeth, as illustrated in details in Figs. 14 and 15, are provided in their faces with packing-strips 139.

Various modes of adjustment of packing-pieces may be employed, such as by means of springs or steam-ducts, as illustrated, or both.

These packing-strips 139 are grooved at their edges to receive side tongues in the tooth-groove, in which they fit, which occupy the side grooves, so as to confine the packing-strips 5 within their seats in the teeth, but allowing sufficient play to permit the packing-strips in the teeth to be forced radially outward in contact with the surface 142 of the cylinders, and thus secure steam-tight joints upon their 10 surfaces, and may be assisted by water-cuts in the cylinders or their surface-pieces.

The ends of the teeth are provided with packing-pieces 275, which have a little end-play beneath their surfaces, thus providing 15 for the difference of expansion and contraction of metals and preventing end binding of the tooth. These pieces fit in the recesses in the ends of the teeth, and are pressed outward by springs 276 or steam; or both may be employed, if desired, to press the packing-pieces 20 in contact with the surface-bearing pieces 142, and form steam-tight joints therewith. In case steam is employed, the construction of the stem of the packing-piece of the hole corresponding 25 should be made in harmony therewith, with water-creases around it.

In the respective heads are packing-rings 277, pressed out by springs 278 in contact with the rim of the wheel, which produce steam-tight joints. These springs have play beneath 30 their surfaces to compensate for expansion and contraction of metals, and thus prevent end binding.

The abutment-rollers 135 are also provided 35 with packing-rings 279 to perform the same office in producing tight joints with play beneath the rings to prevent end binding. These rings press against the plate covering the end of the recess in the abutment-rollers, 40 and produce the tight joint more fully described in other applications of even date herewith.

Fig. 16 illustrates an end view of the tooth with the end packing-piece, 275, removed.

A sufficient number of water-cuts are provided 45 in the respective packing-rings and the surfaces in which they work to prevent leakage of steam.

In Fig. 20 a modified form of this engine is illustrated. Its main feature is a twofold valve 50 instead of the fourfold valve, heretofore described, with induction-ports and engine-easing constructed in harmony therewith. Induction-ports and steam-channels are placed to correspond with the two-faced valve in the 55 respective seats. The construction of this valve and the engine easing or cylinder is simpler than those previously described, and makes a most complete cut-off non-reversible engine. In Figs. 20^a, 20^b, 20^c, 20^d, and 20^e 60 these twofold and two-faced valves are more fully illustrated in sectional and full views. Fig. 20^a is a longitudinal sectional view of one of the valves complete with the stems broken, showing the method of springs to hold the 65 valves proper upon their seats, also the steam-ducts conveying steam between the valve-shanks and frame, in which a little play is al-

lowed to compensate for contraction and expansion, thus preventing the valve from sticking. The frame is grooved between the valve-stems from end to end of the valve for the valve-shanks to fit in. The ends may have stops inserted equal to the thickness of the collars and the ends of the valve-shanks notched to suit, the object of which is to produce steam-tight joints, in combination with the valve packing-rings in the heads. A notch is also turned inside of the collar of the valve-frame, in which the respective flanges fit endwise, steam always working beneath the flanges and the frame to hold them against their respective faces.

150^b represents the valve-frame proper with the stems, and 150^c the adjustable valve-pieces. Two modes of pressing outward the adjustable valve-pieces proper on the face of the valve-seats are shown, such as springs and steam-ducts.

It will be seen that by means of holes in the main frame-work of the valves live steam is supplied to both sides of the valves, thereby producing an equilibrium, while in the four-faced valve, as illustrated in Fig. 1, live steam is conducted to the four opposite surfaces with holes crossing each other, and thus producing 95 an equilibrium therein. In this respect the fourfold valve differs from any heretofore mentioned in any of the previous cases. This four-fold valve is applicable to a non-reversible engine only when the live steam from the boiler 100 direct occupies the opposite four quarters. So, also, is the twofold valve applicable only to a non-reversible engine when counterbalanced by live steam from the boiler direct on each side of the valve.

105 The twofold valve 150^a, Fig. 20, will be made the subject of a separate application.

Having thus described my invention, what I claim as new, and desire to secure by Letters Patent, is—

110 1. The double non-reversible trochilic or rotary engine constructed with two piston-wheels on one shaft, each having two teeth, with the teeth on one wheel opposite the spaces between the teeth of the other wheel, two cut-off valves at opposite points in each cylinder, two valveless discharge-ports at two other opposite points, and automatic cut-off gear, all substantially as herein shown and described.

115 2. A center head with four valve-stem bearings—two on each side—and valve packing-rings, and with adjustable abutment-roller bearing, and their automatic or screw followers, in combination with two toothed piston-wheels and abutment-rollers, for the purpose 120 set forth.

125 3. The end heads having two valve-stem bearings in each head, with valve packing-rings, springs, &c., for forming steam-tight joints endwise and prevent end binding, and the adjustable abutment-roller journal-bearings, with their automatic or stationary followers, in combination with abutment-rollers, two toothed piston-wheels, and condense-water

- channels and cylinder-cocks, substantially as and for the purposes set forth.
4. A trochilic or rotary engine piston-wheel, 132, provided with surface-pieces 141, piston-teeth 136, holding said surface-pieces, packing-strips 139, and springs 274, in combination with the packing-strips 139 and packing-pieces 275, and spring 276, substantially as and for the purposes set forth.
10. 5. A rotary piston-tooth, 136, in combination with packing-strip 139, spring 274, and end packing-piece, 275, spring 276, and water-creases therein, substantially as and for the purposes set forth.
15. 6. In a trochilic or rotary engine, the combination of one or more toothed piston-wheels, two or more recessed abutment-rollers for each of said piston-wheels, straight-toothed gear-wheels 183 184, connecting the shafts of the piston-wheel and abutment-rollers at one end thereof and helical gear-wheels connecting said shafts at the other end thereof, to prevent lost motion, to preserve steam-tight joints, and permit the tightening of all the gear-wheels by longitudinal adjustment of the helical gears, substantially as set forth.
20. 7. The adjustable bearing-segments 261 for the main-shaft bearing, and housing or casing 264, in which they fit, and a ring, 263, having inclines corresponding with the inclines of the backs of the bearing-segments to fit and adjust the same, with screw-thread therein fitting the screw-thread of the bearing casing or housing, and a tooth-gear upon the outer surface of the ring with pinion 265, hollow shaft 266, pin 267, spring 269, gear or ring 271, having serrated face with corresponding serrated ring, 270, and rivet 268, &c., substantially as and for the purpose set forth.
25. 8. The combination of the end head, the shaft-bearing therein, and the removable casing covering said bearing, substantially as and for the purposes set forth.
30. 9. The fourfold cut-off balanced valves, with connected ducts crossing each other through the valves, permitting steam to pass freely to the four opposite recesses in the valves, and thus counterbalance the pressure thereon, substantially as and for the purposes set forth.
35. 10. A removable convex and concaved end 50 of a center head for the purpose of inserting the main-shaft bearings, substantially as and for the purposes set forth.
40. 11. The adjustable segment-bearings, with one or more inclined backs thereon, and housing or casing having mortises corresponding with the projections of the segment-backs, and an encircling ring or rings fitted as described, tooth-gear thereon, and a pinion with its adjuncts to hold all in position, substantially as 55 and for the purposes set forth.
45. 12. The combination of the toothed piston-wheel, recessed abutment-rollers, tappets, valve-levers, and stops, constructed and operating as and for the purposes herein set forth.
50. 13. The combination of the center projections, 142^a, in the end heads with the central projections, 142^a, in the center heads and cylinders, piston-wheels, and main-shaft bearings in each of the cylinder-heads, substantially as specified.
55. 14. A valve-seat bushing, in combination with the fourfold balance-valve, having inlet and exit live-steam ports through the same without any exhaust-ports therein, substantially as and for the purposes set forth.
60. 15. In a rotary engine, a removable piece, 32, having flanges and boss, with bolts 33, for securing it in place, and provided with tongues and grooves, followers 34, springs 36 and 42^a, 80 spring-catch 43^a, and hollow cap-nut 37, substantially as and for the purpose specified.
65. 16. In a rotary engine, the combination of automatically-adjustable bearing-segments with the abutment-roller journals in the heads, substantially as set forth.
70. 17. In a rotary engine, a central main shaft provided with a tapered portion for securing a piston-wheel, having stops therein and corresponding recesses in the wheel, a thread and 90 nut with internally-threaded pins, substantially as and for the purpose specified.
